UNITED STATES PATENT OFFICE.

ALEXANDER WINTON, OF CLEVELAND, OHIO.

CARBURETER.

1,014,551.

Specification of Letters Patent.

Patented Jan. 9, 1912.

Application filed April 3, 1909. Serial No. 487,669.

To all whom it may concern:

Be it known that I, ALEXANDER WINTON, a citizen of the United States, residing at Cleveland, in the county of Cuyahoga and 5 State of Ohio, have invented certain new and useful Improvements in Carbureters, of which the following is a specification, reference being had therein to the accompanying drawing.

10 This invention relates to improvements in carbureters, and particularly pertains to that type of carbureter in which there are two separate air passages, each having a separate oil supply, whereby there are two separate 15 carbureting passages.

The present improvement relates to certain construction and arrangement of parts, which will be described and pointed out hereinafter.

20 Referring now to the drawings, Figure 1, is a perspective view of a carbureter embodying the present improvement. Fig. 2, is a horizontal, sectional view taken through the center thereof. Fig. 3, is a vertical, 25 transverse, sectional view on the line 3—3 of Fig. 2. Fig. 4, is a vertical, transverse, sectional view on the line 4—4 of Fig. 2. Fig. 5, is a vertical, longitudinal, sectional view on the line 5—5 of Fig. 2. Fig. 6, is 30 a horizontal, sectional view on the line 6—6 of Fig. 3. Fig. 7, is a detached, perspective view (partly in section) of the detachable support and lock for the adjustable gaso- 35 lenne regulating valve. Fig. 8, is a detached, perspective view of the gasolene regulating valve. Fig. 9, is a transverse, sectional view on the line 9—9 of Fig. 8. Fig. 10, is an 40 enlarged view showing a part of the casing in section, and the support for the air inlet valve in side elevation. Fig. 11, is a trans- 45 verse, sectional view on the line 11—11 of Fig. 10.

The present improvements, as embodied in the accompanying drawings, consist of an 45 inclosing casing 1, which embraces a gaso- lenne float supply chamber 2. Passing through this casing are two air carbureting passages 3 and 4, and these passages pass around or by the supply chamber 2. The 50 top and bottom walls 4 of the casing constitute the top and bottom walls of the passages 3 and the outer vertical walls 5 constitute the outer walls of said passages, and the inner walls of the passages are formed 55 by the wall of the gasolene supply chamber 2, and the vertical longitudinally extending

webs 5' and 6. The air inlet ends of these passages are each provided with inlet passages 7, and their outlet ends 8 are each provided with controlling throttles or valves 60 9 and 10. Each of the inlet passages 7 is provided with an inwardly opening valve 11, and these valves slide upon an adjustable supporting rod 12. Arranged in the top of the casing 1 and coaxial with the valves 11, 65 are the externally screw-threaded valve-rod supporting members 13. Spiral springs 14 surround the rods 12, and have their lower ends engaging the valves 11, and their upper ends engaging the adjustable members 13. These springs hold the valves normally 70 in contact with the heads 15 of the rods 12, and the tension of these springs upon the valves is regulated by the adjustable members 13, for a purpose to be stated hereinafter. The members 13 have a central longitudinal bore or passage 16 through which the valve-supporting rods 12 pass, and the upper ends are screw-threaded as shown at 75 17, to receive the screw-threaded portions 80 of the rods 12, whereby the rods are adjustable through the members 13. These members 13 are split longitudinally below their heads 18 by longitudinal slits 19, and one of the divided portions is provided with a 85 longitudinal external groove 20, which receives the inner end of a set screw 21. This screw serves to hold the member 13 from rotating after it is adjusted, and by forcing it against the inner wall of the groove as 90 shown in Fig. 11, clamping the valve-supporting rod 12 and holds it to its adjusted position.

As shown, the gasolene supply chamber 2, preferably extends below the casing 1, 95 as shown at 22, and has a centrally located gasolene inlet port 23, which is controlled by means of a valve 24, the stem 25 of which is suitably connected with the float 26. The stem preferably projects through the supply 100 chamber cover 27, which latter serves as a guide for the upper end of the rod to cause the proper seating of valve, and to enable the valve to be operated by hand from the outside for priming, or other purposes. 105 Preferably, the float stem 25 is adjustably connected with the float to permit the gaso- lenne lever to be adjusted. This is accom- 110 plished by having the stem adjustable through the float, and it may be done in any convenient manner. As here shown, it is accomplished by providing the stem 25

2
with several cotter pin openings 28, for a cotter pin 29, which passes through a staple 30 which is attached to the float 26, though it may be accomplished by providing the 5 stem 25 with screw threads where it passes through the float. The projecting end of the valve stem 25 enables the valve to be operated by hand to clear it of any small particles which might prevent it from seating, or free it if for any reason it should stick.

Each of the air carbureting passages 4 is provided with a gasoline inlet nozzle 31 which projects from the bottoms of the passages 4 which in turn communicate with the gasoline supply chamber 2. The flow of gasoline through these nozzles is regulated 10 and controlled by the adjustable valves 33, the stems 34 of which are externally screw-threaded, and mesh with the screw threads 35 of the stem support 36. This support with the valve 33, is removable from the 15 casing by having a screw-threaded end 37 which enters the casing 1, and an angular portion 38 to receive a wrench. A knurled head 39 on the ends of the valve stems 34 enables them to be turned for adjustment in 20 relation to the inlet nozzles 31. For the purpose of holding the valves in their adjusted positions the upper ends 40 of the supports 36 are conical-shaped and slotted, as shown at 41, so that the internal cone-shaped portion 42 of the cap 43 which 25 screws on the outer end of the support 36, will cause the extremity of the support to clamp the valve stem and hold it in its adjusted position. Gasoline is fed to the 30 supply chamber 2 through a passage 44, and a drain passage 45, having a drain cock 46 is provided.

Peculiar shaped gasoline controlling valves for the nozzles 31 are provided. The 45 particular shape is shown in Figs. 8 and 9, and consists in having a triangular shaped portion *a*, a cone-shaped apex *b*, and a horizontal flange *c* at the opposite end of the portion *a*. In the adjustment of this valve, 50 the triangular portion will enter the nozzle and the flange portion *c* can be made to approach or recede from the top of the nozzle as may be required.

The throttle 9 is attached to a shaft 47, 55 the outer end of which projects through the wall of the outlet passages 8 and has attached to it a head 48. This head 48 has an arm 49 carrying an adjustable screw 50, and this screw 50 is adapted to engage a flange 60 or shoulder 51, and thus limit the movement of the arm and the shaft 47 in the direction of the flange 51. A spring 52 is attached to the head 48 at the side opposite the arm 49 by means of a screw or projection 50'. 65 This spring serves to hold the shaft 47, and

the throttle 9 normally in their adjusted position, which is regulated by the said screw 50. The throttle 10 is connected with a shaft 54 which has its inner end loosely interlocking with the adjacent end 47, as 70 shown at 55, whereby the shaft 54 is permitted to have a movement independent of the shaft 47 corresponding to the amount of looseness of the connection 55. The opposite end of the shaft 54 projects through the 75 outlet passage 8 at the opposite side of the casing from the projecting end of the shaft 47, and the projecting end of the shaft 54 is provided with an operating arm or lever 80 56. The outer end of this lever is connected with the throttle-controlling element or lever (not here shown) through the medium of a suitable rod 57. A lug 58 projects from the outer wall of the casing 1 and in the path traveled by the arm 56, and this lug is provided with an adjusting screw 59 adapted to regulate the movement of the arm in the direction of the lug, as shown in Fig. 5. The throttle 9 is set slightly open by means of the adjusting screw 50 sufficient 85 to provide for the minimum speed of the motor, and at this time, the throttle 10 is closed by the throttle-operating lever (not shown) through the rod 57. For increased speed, the throttle 10 is opened independent 90 of the throttle 9 until the throttle 10 is about one-third open, at which point the interlocking connection 55 will then cause the shaft 54 to revolve the shaft 47, which will cause both throttles to then be opened 95 together until the maximum opening position is reached. This arrangement causes the use of one of the carbureting passages for the minimum speed, and this is always held at that adjustment, and then causes the 100 other carbureting passage to be brought into use in conjunction with the first said passage until the interlocking connection 55 is brought into action, at which time the two throttles then have what might be termed a 110 co-acting progressive movement. The use of a single carbureting passage for minimum speed of the motor effects an economy in fuel used, and the use of the other passage for a further increased speed before 115 causing the joint progressive movement of the throttles, also contributes largely to the economy of fuel, in that the single carbureting passage serves to furnish the "gas" for the motor for ordinary speed, with the exception of the small amount furnished by the passage having the throttle 9 which is set for the minimum unloaded speed of the 120 motor.

The positions of the air inlet valves 11 are 125 controlled by the adjustable valve-supporting stems 12, and the tension of the springs 14 are regulated by the adjustable members 13 for the purpose of furnishing the proper amount of air to the carbureting passages 130

at the various speeds of the engine, and to meet the demands of the engine at its various speeds in a way to obtain the most economical and the best result as to the 5 power of the engine.

An annular wire screen 60 is removably and vertically placed within the supply chamber 2 and fits against its vertical wall, and the lower edge of the screen snugly fits 10 against the bottom of the chamber 2. Formed in the wall of the supply chamber at the junction of the solid and bottom walls, is an annular oil supplying groove 61, which 15 communicates with the lateral supply passages to the nozzles 31. This screen serves to prevent the passage through the nozzle ports any sediment or foreign matter which might interfere with the proper operation of the carbureter, or be drawn into the engine cylinder, and the annular groove 61 20 insures ample supply of fluid to the nozzle passages.

No claim is made herein for the valve

mechanism here shown and described, as this will form the subject matter of a divisional application. 25

Having thus described this invention, what is claimed and desired to be secured by Letters Patent, is:—

A carbureter having two horizontal air 30 carbureting passages, a vertically arranged fluid chamber located between said passages at a point intermediate the ends of the horizontal passages, the fluid supply chamber having a separate exit passage extending 35 into each air passage, one end of the passages having air inlet passages at one side of the supply chamber and the other ends having throttles located at the opposite side of the supply chamber. 40

In testimony whereof I affix my signature in presence of two witnesses.

ALEXANDER WINTON.
